UNITED STATES PATENT OFFICE.

WILLIAM F. KIESEL, JR., OF ALTOONA, PENNSYLVANIA.

THROTTLE-VALVE.

1,275,041.

Specification of Letters Patent.

Patented Aug. 6, 1918.

Application filed December 5, 1917. Serial No. 205,830.

To all whom it may concern:

Be it known that I, WILLIAM F. KIESEL, Jr., a citizen of the United States, and residing at Altoona, county of Blair, State of Pennsylvania, have invented certain new and useful Improvements in Throttle-Valves, of which the following is a specification.

This invention relates to throttle valves and has particular reference to locomotive throttle valves of the balanced type, in which the pressure of the steam in the boiler in which the throttle is located assists in the operation of the valve, in order that the manual labor connected with its manipulation may be reduced to the minimum, as well as the wear and tear on the valve parts.

The object of the invention is to provide a device of this class in which the balancing of the main valve of the throttle is attained by simple means, enabling the amount of steam passing through the valve to be very nicely regulated; which is comparatively inexpensive to construct, and in which the manual power necessary for operation is very slight.

The invention will be fully disclosed in the following description taken in connection with the accompanying drawings, in which: Figure 1 is a side view of one embodiment of my invention, part being broken away, the valve being closed and located in the steam dome of a locomotive;

Fig. 2 is a sectional view along the line 35 2—2 of Fig. 1, the valve being shown open.

The casing 10 which incloses or supports the moving parts of the device, is adapted to be attached to or forms a part of the end of the dry pipe when used in connection with a locomotive, its upper end projecting into the steam dome. In the drawings I have shown portions only of the steam dome and boiler as these parts are well known and form no part of the present invention.

In the upper end of the casing 10 is located the main port or inlet port 11 having the removable valve seat 12 secured therein against which the main valve 13 is adapted to seat. Within the casing and axially aligned with the main port 11 is a cylinder 14 having its upper end open and unobstructed and communicating with the exterior of the casing at its lower end through a small or auxiliary port 15, which is also axially aligned

with the port 11 and cylinder 14. Within 55 the cylinder 14, which is stationary and preferably integral with the casing 10, is located a piston 16 closely fitting the same, and having an upwardly extending annular portion 17 telescoping with the downwardly 60 extending annular shank 18 of the main valve 13. The two overlapping portions 17 and 18 of the piston and main valve respectively are secured together by a tapering key 19 so that they comprise a rigid structure. 65

The piston 16 is provided with an axial passage 20 therethrough and ports 21 in the wall of the passage 20 communicate with the interior of the casing, so that when the lower end of the passage 20 is not obstructed steam 70 may freely pass from the underside of the piston 16 through the passage and into the interior of the casing 10.

Extending upwardly through the auxiliary port 15 in the bottom wall of the cylinder 14 and through the passage 20 of piston 16 and an axial opening 22 in the main valve 13, extends a spindle 23 which is prolonged downwardly and operatively connected at its lower end with the throttle lever outside of the boiler, by means of the usual bell crank levers and connecting rods. This spindle 23 has a slot 24 therein for the accommodation of the key 19, said slot being elongated so that the key 19 may move freely 85 up and down therein without engaging its ends. That portion of the spindle 23 which extends through the port 15 in the lower wall of the cylinder is provided with longitudinal grooves or depressions 25, which in certain positions of the spindle allow the steam without the casing to pass upwardly into the cylinder below the piston. To control this passage of steam through the auxiliary port 15, the spindle 23 is provided 90 with an enlarged portion 26 comprising a valve which seats on a circular valve seat 27 on the bottom wall of the cylinder. Thus when the spindle 23 is raised so that the valve 26 is lifted from this seat 27, the steam 100 outside of the casing is free to pass through grooves 25 into the cylinder, but when the valve 26 is seated as in Fig. 1 this inflow is prevented.

Immediately above the valve 26 on the 105 spindle 23 is a portion 28 tapering in the opposite direction which constitutes a valve or plug adapted to close the lower end of the

- passage 20 through the piston 16. This valve 28 controls the passage of fluid from within the cylinder under the piston upwardly through the passage 20 into the casing proper. When the main valve is seated as shown in Fig. 1, and the valve 27 is also seated, the valve 28 is out of contact with its seat on the lower side of the piston, but when the spindle 23 is moved upwardly to 5 open the auxiliary port 15, the valve 28 moves into engagement with its seat and blocks the passage 20 so that the fluid entering through the auxiliary port is trapped beneath the piston 16.
- 10 The upper end of the spindle 23 is provided with a cylindrical portion 29, the upper face 30 of which may be normally flush with the upper face of the main valve 13. The area of the face of the piston 30 is 15 slightly greater than the area of the portion of the spindle 23 which is subjected to the upward pressure of the steam so that the valve 27 remains normally seated due to a greater pressure from above than from 20 below.
- 25 The area of the piston 16 is also slightly greater than the area of the main valve 13 so that when full steam pressure is being exerted on the upper face of the valve and 30 on the lower face of the piston, the piston will exert a sufficiently superior force to raise the valve.

In operating the device, assuming the valve closed as shown in Fig. 1, the spindle 23 is raised, by proper manipulation of the throttle lever without the boiler and steam is admitted to the cylinder below the piston 16 through the port 15, the valve 27 being raised from its seat. Simultaneously the 35 plug or valve 28 closes the lower end of the passage 20 and the steam entering is trapped beneath the piston, which being larger in area than the main valve 13 is forced upwardly to raise the valve from its seat and 40 to allow the steam to enter the casing 10 and pass off through the dry pipe. The spindle 23 may be raised any desired amount by the operator with little effort, the burden of lifting the main valve 13 being borne 45 by the piston 16.

50 When, however, a sufficient amount of steam is passing through the dry pipe the spindle 23 is brought to rest as shown in Fig. 2. When in this position, with the full 55 pressure of the fluid being exerted on both sides of the piston and on the upper and lower surfaces of the main valve, the opposing forces are substantially balanced and the valve remains stationary, resting upon 60 the tapering portion 28 of spindle 23.

The slot in the spindle 23 through which the key 19 passes is of such length that the key does not contact with the ends thereof in all ordinary manipulations of the valve, 65 but if the spindle is given a sudden move-

ment the ends of the slot will be brought in contact with the key to manually assist in operating the valve.

From the above description it may be seen that I have produced a throttle valve which is very simple and practical and one which is very sensitive and easy to manipulate. Obviously variations in construction may be made within the scope of the appended claims without departing from the spirit 70 of the invention and it is obvious that the throttle described may be used to control the flow of other fluids under pressure from their containing tanks as, for instance, compressed air, although as before mentioned, it is primarily intended to be used in connection with steam generating units.

Having thus described the invention what is claimed as new and desired to be secured by Letters Patent is:—

1. In a balanced throttle valve, the combination with a casing having a main port and an auxiliary port, and a cylinder therein open at one end and communicating with the outside of said casing at its other end through said auxiliary port, of a main valve for controlling said main port, a piston in said cylinder having a passage therethrough from one side to the other, said piston being operatively connected to the main valve 90 and having an area slightly greater than the area of said main valve, a manually operable valve controlling the auxiliary port and regulating the passage of steam under pressure therethrough into said cylinder beneath 100 said piston, and a valve controlling the passage of steam through the piston, whereby the steam may be trapped beneath said piston to actuate the same to open the main valve, or may be released to allow said piston 105 to descend and thereby close said main valve.

2. In a balanced throttle valve, the combination with a casing having a circular main port, and a circular auxiliary port, and a cylinder therein open at one end and communicating with the outside of said casing at its other end through said auxiliary port, said main port, auxiliary port and cylinder being in axial alignment, of a main valve 110 for controlling said main port, a piston in said cylinder having a passage therethrough from one side to the other, said piston being operatively connected to the main valve and having an area slightly greater than the area 115 of said main valve, a manually operable valve controlling the auxiliary port and regulating the passage of steam under pressure therethrough into said cylinder beneath said piston, and a valve controlling the passage through said piston whereby the steam 120 under pressure entering through said auxiliary port may be trapped beneath said piston to actuate the same to open the main valve, or may be released to allow said piston to 125 descend and thereby close said main valve. 130

3. In a balanced throttle valve, a casing adapted to be secured to the end of the dry pipe in the steam dome of a locomotive or other steam engine, said casing having a
5 main port and an auxiliary port therein and a cylinder contained within said casing between said ports and axially aligned therewith, said cylinder being open at one end and having communication at its other end with
10 the space outside of said casing through said auxiliary port, of a main valve for controlling said main port, a piston in said cylinder having a passage therethrough from one side to the other, said piston being operatively connected to the main valve and having an area slightly greater than the area
15 of said main valve, a manually operable valve controlling the auxiliary port and regulating the passage of fluid under pressure there-
20 through into said cylinder beneath said piston, and a valve controlling the passage through said piston whereby the fluid under pressure entering through said auxiliary port may be trapped beneath said piston
25 to actuate the same to open the main valve, or may be released to allow said piston to descend and thereby close said main valve.

valve controlling the auxiliary port and regulating the passage of fluid under pressure therethrough into said cylinder beneath said piston, and a second piston connected with said manually operable valve and having one surface exposed to the pressure of the fluid without the casing, whereby said valve is normally held closed. 70

6. In a balanced throttle valve, the combination with a casing having a main port and an auxiliary port, and a cylinder there-in between said ports, open at one end and communicating with the exterior of said casing at its other end through said auxiliary port, said ports and cylinder being axially alined, of a main valve for controlling said main port, a piston in said cylinder having a passage therethrough from one side to the other, said piston being operatively connected to the main valve and having an area slightly greater than the area of said main valve, a manually operable valve controlling the auxiliary port and regulating the passage of fluid under pressure therethrough into said cylinder beneath said piston, and a valve rigidly connected to said manually operated valve, for controlling the passage through said piston, the two last mentioned valves being moved simultaneously in one direction to open said auxiliary port and close the passage through said piston whereby the fluid under pressure may enter through said port and be trapped beneath the piston to raise the same and to open the main valve, or to be moved in the opposite direction to close the auxiliary port and open the passage through the piston to release the fluid under pressure to allow the piston to descend and thereby close said main valve.

7. In a balanced throttle valve, the combination with a casing having a main port and an auxiliary port and a cylinder therein open at one end and communicating with the outside of said casing at its other end through said auxiliary port, of a main valve for controlling said main port, a piston in said cylinder, said piston being operatively connected to the main valve and having an area slightly greater than the area of said main valve, a manually operable valve controlling the auxiliary port and regulating the passage of fluid under pressure therethrough into said cylinder beneath said piston, and means for controlling the volume of fluid in said cylinder below said piston whereby the position of the latter and of the main valve may be regulated. 110 115 120

8. In a balanced throttle valve, the combination with a casing having a main port 125 and an auxiliary port and a cylinder there-in open at one end and communicating with the outside of said casing at its other end through said auxiliary port, of a main valve for controlling said main port, a piston in 130

said cylinder, said piston being operatively connected to the main valve and having an area slightly greater than the area of said main valve, a manually operable valve controlling the auxiliary port and regulating the passage of fluid under pressure therethrough into said cylinder beneath said piston, and manually operable means for con-

trolling the volume of fluid in said cylinder below said piston by permitting the escape 10 of excess fluid, whereby the position of the piston and of the main valve may be regulated.

In testimony whereof I affix my signature.

WILLIAM F. KIESEL, JR.
